UNITED STATES PATENT OFFICE

2,606,919

PROCESS FOR THE CONTINUOUS MANUFACTURE OF LIQUID NITRIC ESTERS

Frederick A. F. Crawford, Aylesbury, Glenageary, Ireland, assignor to Imperial Chemical Industries Limited, a corporation of Great Britain

Original application December 6, 1946, Serial No. 714,626. Divided and this application June 28, 1949, Serial No. 101,834. In Great Britain December 7, 1945

2 Claims. (Cl. 260—487)

1

This invention relates to improved process for the continuous manufacture of explosive liquid nitric esters from rapidly esterifiable liquid polyhydric alcohols and especially to the continuous manufacture of nitroglycerine and the like. More particularly, the invention relates to a process provided with an improved circulatory means for the manufacture of the aforesaid explosive liquid nitric esters, wherein the esterifiable organic liquid compound is continuously nitrated with a nitrating acid medium and the resulting liquid nitric ester is separated from the refuse nitrated acid.

This application is a division of applicant's application Serial No. 714,626, filed December 6, 1946, now U. S. Patent No. 2,579,474.

The object of this invention is to provide a suitable process which may be used with relative safety for the continuous production of liquid explosive nitric esters which includes means for quickly and continuously removing by centrifugal separation the liquid explosive nitric ester from a continuous succession of relatively small quantities of a mixture of said liquid explosive nitric ester and refuse nitrating acid resulting from the interaction of a liquid polyhydric alcohol and nitrating acid.

Other objects and details of the invention will become apparent from the following description when read in connection with the accompanying drawings wherein:

Figure 1 is a vertical section of the general arrangement of apparatus used in this invention, and

Figure 2 is an enlarged vertical section of the mixing vessel forming part of the apparatus.

According to this invention, the process for the continuous manufacture of explosive liquid nitric esters from rapidly esterifiable liquid polyhydric alcohols, comprises continuously introducing the alcohol and nitrating acid into a mixing space, subjecting the incipiently reacted mixture to continuous circulation by impelling it at a rate sufficient to maintain turbulence throughout the circulation out of the lower part of said space through a narrow externally cooled tubular conduit external to said space to a horizontally remote locus at which the reaction is complete and back into the upper part of said space, bleeding off a portion of the substantially completely reacted mixture at said remote locus, and separating by continuous centrifugal action the liquid explosive nitric ester from the bled off portion while the latter is still in emulsion form.

Preferably, the resulting continuously sepa-

rated liquid explosive nitric ester is immediately emulsified with an aqueous washing medium.

As long as the liquid explosive nitric ester remains emulsified in the refuse nitrating acid in its passage between the nitrating vessel and the centrifugal separator, there is no danger of any detonation arising in the centrifugal separator being carried back through the column of liquid to the nitrator. The proviso according to the present invention that the incipiently reacted mixture is to be impelled at a rate sufficient to maintain turbulence throughout the circulation of the reaction mixture past a horizontally remote locus makes it possible for the nitrating vessel and the centrifuge to be sufficiently distanced so that no explosion debris from either is likely to reach the other.

Apparatus suitable for the process set forth supra comprises a mixing vessel having a lower portion of larger diameter accommodating a rotary impeller and an upper neck portion of smaller diameter open at the top accommodating the shaft of the said impeller, inlets for the liquid reagents, an external circulation pipe jacketed over substantially its whole length and leading from the vessel at the level of the impeller to a horizontally remote locus and returning into the neck of said vessel, a continuous centrifugal separator in the vicinity of said locus at a lower hydrostatic level than said vessel and a branch communication from a portion of said external circulation pipe at said locus entering said centrifugal separator. The separator is provided with an outlet for the refuse acid and an outlet for the separated liquid explosive nitric ester which leads to re-emulsifying apparatus in which said ester is emulsified in an aqueous washing liquid in close proximity to the separator. The centrifugal separator and the re-emulsifying apparatus are preferably shielded by a surrounding baffle structure, and a baffle structure is preferably interposed between the mixing vessel and the remote part of the circulating pipe. The external circulating pipe passes through the latter valve. Also, the impeller shaft of the mixing vessel may be provided, if desired, with stirrer blades.

Referring to Figures 1 and 2 of the accompanying drawings, a mixing vessel 1 is provided with a rotating impeller 2, an outlet 3 at the level of the impeller provided with a jacketed covering, and a return or inlet portion 4. The jacketed outlet 3 extends horizontally to a remote locus such as that locus designated by the numeral 3' and then returns horizontally in con-

nection with the return jacketed pipe 4. A bleed-off pipe 5 is provided at the remote locus 3' and is connected to a centrifugal separator 6. A pipe 7 is provided for leading the separated liquid explosive nitric ester delivered through an outflow pipe 15 in water by means of a water jet 16 to a washing tank not shown in the drawings since it forms no part of this invention. Pipe 8 is a refuse acid outflow pipe and 9 is an emergency run-away cock. A concrete lined trench 10 provided with a concrete explosion baffle 11 running transversely across the trench functions to separate the mixing vessel and centrifuge by a considerable distance and to provide a means for preventing any explosive debris from either of the vessels reaching the other vessel. An overflow gutter 18 and a concrete shielding structure 12 are provided for the centrifugal separator 6 for reasons explained hereinafter.

As best seen in Figure 2, outer walls of the jackets 3a and 4a are provided about pipes 3 and 4, respectively, and thus provide a means for cooling the circulated reaction mixture. Inlet pipes 13 and 14 are provided for the liquid polyhydric alcohol and the nitrating acid, respectively. Bottom 17, forming the bottom closure for the mixing vessel 1, may be destroyed by means not shown if an emergency should arise requiring that the contents of the mixing vessel be emptied into the trench 10.

The invention has the advantage that no matter how far distant is the locus from which the stream is bled off to the separator, the whole stream circulating from the mixing vessel to said locus and back again is maintained in emulsion by its turbulent flow. As the distance the emulsion has to travel from said locus to the separator, over which it is not maintained in turbulent flow by the impelling means may be made very short, it follows that the horizontal distance between the separator and the mixing vessel may be made very considerable without any separation of the emulsion travelling between the two vessels taking place, and hence without the possibility of a detonation in one of the vessels being communicated through the

liquid to the other. Moreover, the separator and the mixing vessel may be so positioned that should a detonation occur in one of these, its force will not be sufficient to injure the operator situated beside the other.

The description of the process of this invention and the apparatus used therefor is for the purpose of illustration only and is not of limitation.

I claim:

1. A process for the continuous manufacture of explosive liquid nitric esters from rapidly esterifiable liquid polyhydric alcohols which comprises continuously introducing the alcohol and nitrating acid into a mixing zone, subjecting the incipiently reacted mixture to continuous circulation by impelling it, at a rate sufficient to maintain turbulence throughout the circulation, from the lower part of said zone to a horizontally remote locus at which the reaction is complete and back into the upper part of said zone, bleeding off a portion of the completely reacted mixture at said remote locus; and separating by continuous centrifugal action the liquid explosive nitric ester from the bled off portion while the latter is still in emulsion form.

2. A process as set forth in claim 1, wherein the resulting continuously separated liquid explosive nitric ester is immediately emulsified with an aqueous washing medium.
